(57) **CLAIM**

The ornamental design for a diaper changer, as shown and described.

DESCRIPTION

FIG. 1 is a three-dimensional view of a diaper changer embodying the invention in its fully unfolded in-use configuration;

FIG. 2 is a top plan view thereof;

FIG. 3 is an underside view thereof;

FIG. 4 is a right side elevational view of the diaper changer, viewed from the bottom in the orientation of FIG. 2;

FIG. 5 is a left side elevational view of the diaper changer, viewed from the top in the orientation of FIG. 2;

FIG. 6 is a first end elevational view of the diaper changer, viewed from the left in the orientation of FIG. 2;

FIG. 7 is a second end view of the diaper changer, viewed from the right in the orientation of FIG. 2;

FIG. 8 is a three-dimensional view of the diaper changer of FIG. 1 in its folded up transportation and storage configuration;

FIG. 9 is a top plan view thereof;

FIG. 10 is an underside view thereof;

FIG. 11 is a first side elevational view of the diaper changer in its folded up configuration, viewed from the right in the orientation of FIG. 9;

FIG. 12 is a second side elevational view of the diaper changer, viewed from the left in the orientation of FIG. 9;

FIG. 13 is a first end elevational view of the diaper changer in its folded up configuration, viewed from the top in the orientation of FIG. 9; and,

FIG. 14 is a second end elevational view of the diaper changer in its folded up configuration, viewed from the bottom in the orientation of FIG. 9.
